UNITED STATES PATENT OFFICE

MAXWELL C. MAXWELL, OF STAMFORD, CONNECTICUT, ASSIGNOR TO THE YALE & TOWNE MANUFACTURING COMPANY, OF STAMFORD, CONNECTICUT

DESIGN FOR A PADLOCK

Application filed May 4, 1929. Serial No. 31,101. Term of patent 14 years.

To all whom it may concern:

Be it known that I, MAXWELL C. MAXWELL, a citizen of the United States, and resident of Stamford, in the county of Fairfield and State of Connecticut, have invented a certain new, original, and ornamental Design for a Padlock, of which the following is a specification, reference being had to the accompanying drawing, forming part thereof.

Fig. 1 is a face view of the padlock showing my new design. Fig. 2 is a side view of the padlock; and Fig. 3 is a bottom view of the same.

I claim:

The ornamental design for a padlock, substantially as shown.

Signed at Stamford, in the county of Fairfield and State of Connecticut, this first day of May, A. D. 1929.

MAXWELL C. MAXWELL.
